UNITED STATES PATENT OFFICE

122,760

DESIGN FOR A FOOD STORAGE RECEPTACLE FOR A REFRIGERATOR OR THE LIKE

Ralph E. Kruck, Springfield, Mass., assignor to
Westinghouse Electric & Manufacturing Com-
pany, a Pennsylvania corporation

Application June 1, 1940, Serial No. 92,747

Term of patent 7 years

To all whom it may concern:

Be it known that I, Ralph E. Kruck, a citizen of the United States, residing at Springfield, in the county of Hampden and State of Massachusetts, have invented a new, original, and ornamental Design for a Food Storage Receptacle for a Refrigerator or the like, of which the following is a specification, reference being had to the accompanying drawings, forming a part thereof.

Fig. 1 is a front elevational view of the food storage receptacle, showing my new design;

Fig. 2 is a side elevational view of the same;

Fig. 3 is a top plan view of the food storage receptacle; and,

Figure 4 is a front perspective view of the same. The side of the food storage receptacle not shown is identical with the side illustrated and the rear of the food storage receptacle is plain.

The dominant feature of the design resides in the portions of the food storage receptacle shown in full lines.

I claim:

The ornamental design for a food storage receptacle for a refrigerator or the like, substantially as shown and described.

RALPH E. KRUCK.
